Patented Sept. 5, 1922.

3 SHEETS—SHEET 3.

UNITED STATES PATENT OFFICE.

RICHARD M. CRAIG, OF SAN ANTONIO, TEXAS.

METHOD OF AND APPARATUS FOR PRODUCING TRANSFORMATION EFFECTS.

Application filed June 11, 1919. Serial No. 303,507.

To all whom it may concern:

Be it known that I, RICHARD M. CRAIG, a citizen of the United States, residing at San Antonio, in the county of Bexar and State of Texas, have invented certain new and useful Improvements in Methods of and Apparatus for Producing Transformation Effects, of which the following is a specification.

10 This invention relates to a method of and apparatus for producing transformation effects, the invention being applicable to stage scenes, stage settings, the production of apparitions, illusions, changes in the form, 15 shape, size, condition, location, etc. of performers or other animate objects or of inanimate objects and to "crazy house" transformation effects.

In the production of plays or vaudeville sketches, it not infrequently happens 20 different scenes of action should follow one another in close sequence in order that the continuity of the plot of the play or sketch will not be interrupted. Up to the present time, in changing from one scene of action 25 to another, it has been necessary to resort either to the use of drop curtains, as for example in changing from an interior scene to a street scene, and then probably back to 30 a different interior scene, or to darken the stage for the length of time required to make the necessary shifts of scenery. In either event there is a suspension of action 35 for a longer or shorter period of time which interrupts the train of thought and is therefore annoying and disconcerting. Furthermore, even though the stage be momentarily darkened to permit of a shifting of the 40 scenery, the darkness is never so complete as to entirely conceal the movements which take place and there is almost invariably some attendant distracting noise incident to the shifting of the scenery. Of course, where 45 a scenic curtain is employed for the purpose of effecting a change in scene, the change and the means whereby it is brought about is clearly visible so that the smoothness of action of the play is disturbed by the extraneous mechanical factor introduced. As 50 applied to transformation changes in stage scenic effects, it is therefore an object of the present invention to evolve a method whereby such changes may be effected instantly, noiselessly, and without the actual 55 shifting of scenery or the raising or lowering of scenic curtains.

Another object of the invention is to evolve a method whereby as many as six different changes in scenic effects may be brought about in the advantageous manner 60 mentioned above so that it is probable that in acting some plays, a single setting of the stage may be all that is required during the entire acting of the play although to the spectators there may be as many as six totally different changes of scenery.

Another object of the invention is to evolve a method whereby changes in scenic effects may be produced in the manner stated 70 accompanied by illumination of the stage setting in light of different colors each appropriate for the particular scenic effect to be produced. Thus while the carrying out of the method of the invention is dependent upon flooding of the stage settings in light 75 of different colors to produce the changes in the scenic effects, it is practicable to so balance the colors selected that each will be appropriate for the particular scenic effect produced when the stage setting is illuminated by light of that particular color.

In vaudeville work various crude attempts have been made to bring about transformation effects while the performers are acting their parts. For example a dancer, tight-wire performer, trapeze performer, and the like, may effect a change of costume in full view of the audience so as to bring about the pleasing effects which might be expected 85 from the exhibition of a variety of costumes. Heretofore, however, this has been accomplished solely by the actual removal of an outer costume so as to expose to view an inner costume, and because of the body movements necessary to effect the removal of the 90 outer costume, there is rendered necessary a more or less prolonged interruption of the dancing or other performing movements. It is therefore also an object of the invention to evolve a method whereby transformation 100 effects of this nature may be brought about instantaneously, without any actual removal or donning of costumes, and without any interruption whatsoever in the dancing or other performing movements. Thus it 105 is possible, as will presently be more specifically pointed out, to not only effect the appearance of a complete change in costume of a performer, as for example the complete removal of a skirt dancer's costume from a 110 dancer leaving the dancer apparently in tights, but also to bring about the appear-

ance of instantaneous rehabilitation of the dancer.

It is a further object of the invention to provide for transformation effects of even 5 a more startling character than that mentioned above, as for example the apparent instantaneous transformation of a performer on the tight-wire into a performing skeleton, the apparent transformation of a person 10 formed of stout built to one of slim built, etc.

In the operation of that class of amusement device commonly known as "crazy houses" attempts have been made to bring 15 about transformation illusions but usually by some mechanical means more or less liable to result in injury to the spectators. Furthermore, where such illusions are brought about by mechanical means the effect of 20 mystification which is intended to be produced, is greatly lessened unless the functioning of such means is completely concealed or otherwise rendered unnoticeable. Furthermore, where mechanical means are 25 employed for bringing about, for example, confusing changes in the surroundings within a room of such an amusement house, any change or variation in the order or arrangement of the surroundings cannot be effected 30 except at a considerable cost. For example, if in a room of such a house mechanical means is provided for moving a chair from one place to another, the chair must always move between its two determined positions 35 and if it is to be moved between any other two positions, the mechanical means for moving the chair must be rearranged or some other more or less expensive means must be resorted to for bringing about the desired 40 variation. It is therefore also an object of the present invention to evolve a method whereby the surroundings in an amusement house of this class may be caused to apparently move about in a most mysterious 45 manner, appear and disappear, change their shape, change their size, or go through various other changes in location, form, and the like, without the employment of any mechanical means whatsoever.

50 In connection with the foregoing it is also an object of the invention to evolve a method whereby various articles of furniture or other objects constituting the surroundings in such a room, may be caused to 55 apparently appear and disappear, instantly move from one place to another, or apparently go through various other mystifying changes, even though the spectators should actually move the articles about in 60 endeavors to ascertain the nature of the means whereby the illusions are brought about.

Where illusions of the nature mentioned above are brought about by mechanical means, the number of changes which may

be brought about or apparently brought about in the location, position, or condition of objects is necessarily limited. Thus if a change is to be brought about or apparently brought about in the location of 70 a chair, for example more or less complicated mechanism would be necessary even to effect a movement of the chair between two positions. A movement of the chair from one position to a second position and then to a 75 third position would, of course, necessitate the employment of an even more complicated mechanism. Therefore, it is a further object of the invention to evolve a method whereby, without the employment of any 80 mechanical means whatsoever, there may apparently be brought about as many as twelve different changes in position of a chair or other object.

In the accompanying drawings:

85 Figure 1 is a perspective view illustrating a scenic curtain which is to be employed in the carrying out of the invention;

Fig. 2 is a detail vertical sectional view 90 through a portion of the curtain;

Fig. 3 is a front view of another curtain;

Fig. 4 is a view illustrating a dancer and manner in which the apparent change in costume may be effected;

Fig. 5 is a view similar to Fig. 4 illustrating the manner in which a performer may apparently be transformed into a skeleton;

Fig. 6 is a view showing the interior of a 100 room of a "crazy house" and illustrating the manner in which various transformation changes may be brought about.

Figs. 1, 2 and 3 of the drawings illustrate the applicability of the invention in 105 effecting changes in stage scenery and while in the two specific examples illustrated and to be hereinafter described, the scenery is in the nature of a full width and full length scenic curtain, it will be understood that various other surfaces may be employed, as for example, a wing, flat or the like. In Figs. 1 and 2 the numerals 1 indicates in general a scenic curtain of any 110 desired dimensions and which curtain is of two ply form comprising a ply or sheet 2 of cloth preferably white in color and translucent and so woven or treated that it will constitute a reflecting surface under conditions to be presently explained. In addition to the ply or sheet 2 the curtain comprises a ply or sheet 3 which is of netting or other material of a reticulated nature and which constitutes a diffractive medium 115 under conditions which will presently be described. The two component parts of the curtain are disposed face to face with the sheet 3 facing the front of the stage so that the curtain may be illuminated by light rays transmitted through the sheets 2 and 120 130

3 or by light rays reflected from the sheet 2 through the sheet 3. Painted in transparent coloring fluids upon the rear face of the sheet 2 are two different scenes, and 5 depicted upon the outer face of the sheet 3 are another two different scenes. The scenes upon the sheet 2 are in different colors complementary to each other as for example blue and yellow. Likewise the 10 scenes upon the sheet 3 are in two different colors complementary to each other, as for example, the colors just mentioned. For example a street scene and a railway station scene might be painted in indiscriminate relation to each other upon the 15 sheet 2, and upon the sheet 3 might be depicted a landscape and a scene representing a country home. By any suitable arrangement of electric bulbs or other illuminating devices, the curtain is adapted 20 to be flooded from the rear selectively with light of colors complementary to the colors of the scenes painted upon the sheet 2, and from the front with light of colors complementary to the colors of the scene upon the sheet 3. For example, as indicated more or less diagrammatically in Fig. 2 of the drawings, yellow lights 4 and blue lights 5 may be arranged at the rear side of the 25 curtain 1, and yellow lights 6 and blue lights 7 may be arranged at the forward side of the said curtain.

In the arrangement above described, when the curtain is illuminated by the yellow lights 4 the scene in yellow upon the sheet 2 will be absorbed but the scene in blue upon the said sheet will be rendered visible, the light rays in this instance passing through the sheets 2 and 3. Likewise when 30 the curtain is illuminated by the blue lights 5, the scene in blue upon the sheet 2 will be absorbed and the scene in yellow will be displayed. In both of these instances the transmitted light rays passing through the sheet 3 will wash out or render indistinguishable the scenes upon the said sheet 3 due to the diffractive nature of the sheet. Consequently either scene upon the sheet 2 35 may be displayed by flooding the curtain with light from the bulbs at the rear thereof and which bulbs are of colors complementary to the color of the scene to be displayed. When the yellow lights 6 are turned on, the curtain will be flooded with light from 40 the front and the light rays will be reflected from the surface of the sheet 2 through the sheet 3 thus washing out the scene in yellow upon the said sheet 3 and exposing to view the scene in blue. On the other hand when the curtain is illuminated 45 by the blue light 7, the scene in blue upon the said sheet 3 will be washed out and the scene in yellow will be exposed.

It will be understood from the foregoing 50 that an instantaneous change in

scenic effects may be produced by a selective use of the lights 4, 5, 6 and 7, the changes being effected in a noiseless manner and without any interruption in the acting of the plays.

By a careful selection of colors, two selected complementary colors may be employed at the rear of the curtain and two different complementary colors may be employed at the front of the curtain. Of course, when 70 the curtain is illuminated with yellow light, a daylight effect will be produced and when illuminated with blue light, a moonlight or night effect will be produced. Of course, by a judicious selection of colors, other effects 75 may be produced, as for example a sunset effect by the employment of red lights.

In the arrangement shown in Fig. 3 of the drawings the numeral 8 indicates in general a scenic curtain upon the face of which 80 are painted, indiscriminately with relation to each other, three different scenes, as for example a water scene, a landscape, and a village scene, these scenes being respectively in three different colors. For example, the 85 water scene may be painted in peacock green, the landscape in magenta, and the village scene in yellow. All three scenes are painted upon one side of the curtain and either upon the front or rear side thereof. 90 In order to provide for illumination of the curtain so as to selectively expose the scenes, any suitable illuminating devices may be employed and in Fig. 3 the numerals 9, 10 and 11 indicate electric lamps which are colored respectively dark red, blue inclining to violet, and yellowish green. Various other 95 selections of colors will serve in carrying out the invention and the selection just stated is, of course, to be considered only 100 as an example. The principle involved, however, is that by a proper selection of colors, illumination of the curtain in light of one color will serve to wash-out two of the scenes upon the curtain, exposing to view the third 105 scene. Thus each of the curtain illuminating lamps 9, 10 and 11 is of a color complementary or substantially complementary to the color in which one of the scenes upon the curtain is painted whereas this color is capable 110 of absorbing or washing out the colors in which the remaining two scenes are painted. For example, when the curtain is illuminated by the lamp 9, the landscape in magenta and the village scene in yellow will be 115 absorbed or washed out but the water scene which is in peacock green, will be exposed to view; when the curtain is illuminated by the lamp 10, the village scene will be visible but the water scene and landscape will be 120 absorbed or washed out; and, when the lamp 11 is employed to illuminate the curtain, the landscape will be rendered visible but the water scene and village scene will be washed out or absorbed.

In this instance as in the 130

arrangement shown in Figs. 1 and 2 of the drawings, an instantaneous change in scenic effect may be produced merely by the selective flashing on of the lights 9, 10 and 11.

5 Figs. 4 and 5 of the drawings illustrate the adaptation of the invention to vaudeville work. In Fig. 4 for example, a dancer will be dressed in green tights and in a red dancing costume, the latter some thin and translucent or semi-transparent cloth or other material. By an arrangement of footlights or other illuminating means, the dancer is to be flooded selectively with light of different colors. For example in Fig. 4 of the drawings the numerals 12 and 13 indicate electric bulbs which are respectively red and green. When the green light 13 is in use, the dancer will appear clothed in the dancing costume for the reason that the color of this garment 10 is complementary to the color of the light rays given off by the said lamp 13. While the dancer is performing, and without any interruption whatsoever in her dancing movements, the lamp 13 may be extinguished 15 and the lamp 12 brought into use whereupon the red light rays emitted therefrom will absorb the red of the dancing costume apparently causing this garment to completely disappear. Of course by extinguishing the lamp 12 and again flashing on the lamp 13 20 the garment may be instantly brought back into view.

In Fig. 5 of the drawings there is shown a performer, as for example a tight-wire 35 walker, strong man, acrobat or the like either painted or clothed in one of the primary colors, as for example green and also having painted upon him or upon his costume, in the complementary color, as for example green, the representation of the frame 40 of a skeleton. Lamps 14 and 15, respectively red and green in color, are provided for selectively flooding the performer with light of these two colors and when the red lamp 45 14 is in use, the performer will appear in his normal condition and stature. However, when the green lamp 15 is flashed on, the green upon the performer or his costume will be absorbed and only the red coloring 50 will be visible so that the performer will appear to have been instantly changed into a skeleton, meanwhile uninterruptedly going through his performance.

Fig. 6 of the drawings illustrates one 55 mode of application of the invention in obtaining transformation effects in "crazy houses" and like places of amusement. In this figure there is represented the interior of a room having various pictures 16 upon 60 its walls some of which may be for example in peacock green; others in magenta, and others in yellow; a plurality of windows, as for example three, indicated by the numeral 17, may be painted upon one of the walls, the frame of one window being, for example,

in peacock green, that of another window in magenta, and that of the third window in yellow; one wall or a portion thereof may be left plain except for the image of a dragon or other animate thing inclined to 70 inspire fear; an image or representation of a prison door, 19, may be painted upon one wall of the room in one color, as for example peacock green, an image 20 of a tall person may be painted as though behind the 75 bars of the door in another color as for example magenta, and an image 21 of a short person may likewise be painted as though behind the bars of the door in a third color, as for example yellow. Likewise the various 80 articles of furnishing such for example as the chairs 22, the tables 23 and 24, the couch 25, rugs 26 and 27, etc. which are actually arranged within the room may be painted in different colors, some for example in peacock green, others in magenta and others in yellow; and, a portion of the floor may be covered with a rug 28 having a design of one kind in peacock green, a design of another kind in magenta, and a design of a third 85 kind in yellow, the remainder of the floor, for example that portion in front of the representation of the cell door 19, being, if desired, painted to resemble bricks of various sizes or shapes as indicated by the number 29, those of one size or shape being represented in one color, those of another size or shape in a second color, and those of a third size or shape being represented in a 90 third color. Arranged about the ceiling or 100 in any other convenient place or places about the room are illuminating devices, such for example as electric lamps 30, 31 and 32, these lamps being, for example, respectively dark red, blue inclining to violet, and yellowish 105 green. From what has been stated before it will be understood that when the lamps 30 are, for example, flashed on, all of the objects of the room which are in peacock green will be brought to view and clearly distinguishable but all other objects, in magenta and yellow, will be rendered invisible. Likewise when the lamps 31 are flashed on, all of the objects in yellow will be rendered visible and all of the other objects in peacock 110 green and magenta will be rendered invisible, and when the lamps 32 are flashed on, all objects in magenta will be visible and all other objects which are in peacock green and yellow will be rendered invisible. Thus, 115 by flashing on and off the lights 30, 31 and 32, in a regular or irregular order, the objects and furnishings within the room and the images upon the walls will be caused to appear and disappear, to shift or jump about 120 from place to place, or to become transformed in various mysterious manners. The several features illustrated in Fig. 6 are caused to be taken merely as an example of several of an unlimited number of possible 125 130

arrangements which might be made. Of course, furthermore the particular idea involved is not limited to association with a room provided with ordinary furnishings, 5 as the idea might be extended to the representations of the interior of caves, submarine caverns, etc.

It will be understood, furthermore, that the methods of the invention are applicable 10 in effecting the appearance of transformation of both animate and inanimate objects.

Having thus described the invention, what is claimed as new is:

1. The method of effecting the appearance 15 of transformation of animate and inanimate objects which comprises representing the object per se in different colors in its different forms and displaying the object successively in the presence of different light 20 media each capable of absorbing all but a respective one of the colors in which the object is represented.

2. The method of effecting the appearance 25 of transformation of animate and inanimate objects which comprises representing one portion of an object per se in one color, another portion in another color, and displaying the object successively in the presence of different colored light media each 30 capable of absorbing a respective one of the colors.

3. The method of effecting the appearance 35 of transformation of animate and inanimate objects which comprises representing the object per se in one condition in one color and in another condition in another color, and displaying the object successively in the presence of different colored light media each 40 capable of absorbing a respective one of the colors in which the object is represented.

4. The method of effecting the appearance 45 of transformation of an assemblage of objects which comprises representing the objects per se in different colors, and displaying the objects successively in the presence of different colored light media each capable of absorbing all but a respective one of the first mentioned colors.

50 5. The method of effecting the appearance

of transformation of an assemblage of objects which comprises representing one object per se in one color and another object per se in another color, and displaying the objects successively in the presence of different colored light media each complementary to one of the first mentioned colors. 55

6. The method of effecting scenic changes which comprises the representation of different scenes in different colors upon a translucent scenic surface, the representation of different scenes in different colors upon a diffractive scenic surface in juxtaposition to the first mentioned surface to receive light reflected therefrom, illuminating the scenic 60 surface by light rays of different colors transmitted through the first mentioned scenic surface and each capable of absorbing one of the first mentioned colors, and displaying the diffractive scenic surface in 65 light rays of different colors by reflection, each capable of absorbing one of the first mentioned colors.

7. The method of effecting the appearance 75 of transformation of animate objects which comprises representing the object per se by the actual coloring thereof or by costume, in different colors in different forms, and displaying the object successively in the presence of different colored light media each 80 capable of absorbing all but a respective one of the colors in which the object is represented.

8. In an amusement house, a room or the like, objects in various different colors arranged therein, and means for illuminating the room or the like, selectively in different colors each capable of absorbing all but a respective one of the colors in which the objects are represented. 85 90

9. A composite scenic surface comprising a translucent surface bearing representations of different scenes in different colors, and a diffractive surface in juxtaposition to the first mentioned surface to receive light 95 reflected therefrom and bearing representations of different scenes in different colors.

In testimony whereof I affix my signature.

RICHARD M. CRAIG. [L. S.]
